Primary Examiner — Richard E Chilcot**CLAIM**

We claim the ornamental design for an integrated mask and hood, as shown and described.

DESCRIPTION

FIG. 1 is a front view of the integrated mask and hood;
FIG. 2 is a right side view of the integrated mask and hood
shown in FIG. 1;
FIG. 3 is a left side view of the integrated mask and hood
shown in FIG. 1;
FIG. 4 is a top view of the integrated mask and hood of the
present invention; and,
FIG. 5 is a rear view of the integrated mask and hood of the
present invention.
In the drawings, the broken lines shown in FIGS. 1–5 depict
portions of the design that form no part of the claim.
